US00D488774S

(12) **United States Design Patent** (10) Patent No.: **US D488,774 S**
Zufall et al. (45) Date of Patent: **** Apr. 20, 2004**

(54) **RECHARGEABLE BATTERY**

(75) Inventors: **Scott W. Zufall**, Kalamazoo, MI (US);
David E. Hershberger, Kalamazoo, MI (US)

(73) Assignee: **Stryker Corporation**, Kalamazoo, MI (US)

(**) Term: **14 Years**

(21) Appl. No.: **29/155,857**

(22) Filed: **Feb. 19, 2002**

(51) LOC (7) Cl. **13-02**

(52) U.S. Cl. **D13/103**

(58) Field of Search **D13/103; 429/96-100, 429/159, 163, 176**

(57) **CLAIM**

The ornamental design of a rechargeable battery, as shown and described.

DESCRIPTION

FIG. 1 is a pictorial view of the rechargeable battery of this invention;

FIG. 2 is a front view of the rechargeable battery of FIG. 1; FIG. 3 is a rear view of the rechargeable battery of FIG. 1; FIG. 4 is a left side view of the rechargeable battery of FIG. 1;

FIG. 5 is a right side view of the rechargeable battery of FIG. 1;

FIG. 6 is a top view of the rechargeable battery of FIG. 1; FIG. 7 is a bottom view of the rechargeable battery of FIG. 1; and,

FIG. 8 is a fragment of FIG. 1.

The broken lines above the base in FIGS. 2, 3, 5 and 6 are included for the purpose of illustrating a portion of the battery that forms no part of the claimed design.

1 Claim, 8 Drawing Sheets
